UNITED STATES PATENT OFFICE.

LEON BLOWER, OF NEW YORK, N. Y.

AUTOMATIC SWITCH-SHIFTER.

SPECIFICATION forming part of Letters Patent No. 756,820, dated April 12, 1904.

Application filed August 7, 1903. Serial No. 168,578. (No model.)

To all whom it may concern:

Be it known that I, LEON BLOWER, a citizen of the United States, residing at 333 East Sixteenth street, New York, county of New York, 5 State of New York, have invented certain new and useful Improvements in Automatic Switch-Shifters, fully described and represented in the following specification and the accompanying drawings, forming a part of 10 the same.

The present invention relates to means for shifting the switch-point in a street-car track; and the invention consists in means for locking the switch-point when shifted, combined 15 with means for shifting the switch from the platform of a car upon the track.

In this invention the switch is shifted by connection to tread-plates arranged near the rail of the track and operated by pressure- 20 rolls sustained upon the car-platform and depressed to engage the tread-plates at the pleasure of the car-driver.

The invention will be understood by reference to the annexed drawings, in which—

25 Figure 1 is a diagram showing part of a car upon the track with the switch shifting and locking mechanism in elevation. Fig. 2 is a cross-section adjacent to the tread-plates. Fig. 3 is a cross-section of the main rail and 30 the switch-point adjacent to the locking mechanism, the switch-point being shown opened. Fig. 4 is a section of the main rail and switch-point adjacent to the shifting device, the switch-point being open; and Fig. 5 is a plan 35 of the track with the switch shifting and locking mechanism shown in dotted lines beneath the same.

a designates the track-rails to which the switch-point *a'* is applied; *b*, the platform of 40 a car, only one of the car-wheels *c* being shown. Tread-plates *d* *d'* are shown mounted to slide vertically at opposite sides of the rail upon which the switch-point is pivoted, and two levers *h*, provided with rolls *h'*, are pivoted upon the platform *b* and provided with 45 treadles *i* and *j* to force down either of the rolls at the pleasure of the driver to depress the corresponding tread-plate. The rolls are both held normally raised by spring *k*. The 50 tread-plates are connected by their vertical

guide-bars with the opposite ends of an arm *l* upon the rock-shaft *m*, which is mounted in bearings *n* beneath the rail *a*. The movement of the tread-plates oscillates the rock-shaft *m*.

The switch-point *a'* is provided upon the 55 under side with a transverse rack *o*, and a segment *q* is fitted loosely upon the rock-shaft and provided with dogs *r*, which contact when the rock-shaft moves in opposite directions with a stud *s* upon the segment *p*. The switch-point is shown provided upon the under side with a notch or socket *e*, and bell-crank *f* are pivoted in bearings at opposite sides of the rock-shaft and provided upon the ends 60 with lugs *e'*, adapted to engage the socket *e*, and thus form bolts to lock the switch-point in place. The bolts are so situated that one of them will engage the socket in either the open or closed position of the switch-point. The bell-crank are connected by links *g* to 70 an arm *g'* upon the rock-shaft so that they are moved alternately in opposite directions by the oscillation of the shaft. To permit the bolts to be withdrawn from the socket in the switch-point before the latter is shifted by the 75 segment *p*, a space for clearance or lost motion is provided between the dogs *r*, so that the rock-shaft may move sufficiently to retract the bolt before the dog contacts with the stud *s* and oscillates the segment to shift the 80 switch-point. The switch-point is thus locked when brought to its final position and is unlocked before it is shifted again. The invention thus provides means for shifting the 85 switch-point and locking the same by the mere operation of the ordinary treadle upon the car-platform.

Having thus set forth the nature of the invention, what is claimed herein is—

1. In a switch-shifter, the combination, with 90 two tread-plates and a rock-shaft actuated thereby with connections to the switch-point for shifting the same, of a socket in the switch-point to receive a bolt, and two bolts actuated alternately by the rock-shaft to lock the switch-point in its open and closed positions.

2. In a switch-shifter, the combination, with 95 two tread-plates and a rock-shaft actuated thereby with connections to the switch-point for shifting the same, of two bell-crank piv- 100

oted at opposite sides of the rock-shaft and provided with bolts to engage the switch-point in its open and closed positions, and an arm upon the rock-shaft connected with the 5 said bell-crank to operate them alternately.

3. In a switch-shifter, the combination, with two tread-plates and a rock-shaft actuated thereby, of a rack upon the switch-point, a toothed segment fitted loosely to the rock- 10 shaft and engaging such rack, dogs secured upon the rock-shaft to oscillate the segment, two bell-crank pivoted at opposite sides of the rock-shaft and provided with bolts to engage the switch-point in its open and closed

positions, connections from the rock-shaft to 15 such bell-crank to actuate them alternately, and the dogs having play or lost motion in their connection with the toothed segment to permit the retraction of the bolts before the switch-point is shifted.

In testimony whereof I have hereunto set my hand in the presence of two subscribing witnesses.

LEON BLOWER.
